US00D373737S

United States Patent [19]

Kurisaki et al.

[11] Patent Number: Des. 373,737

[45] Date of Patent: **Sep. 17, 1996

[54] **SOLID STATE PRESSURE DETECTOR**

[75] Inventors: **Shogo Kurisaki; Masao Kataoka; Kuniko Suzuki**, all of Ibaraki, Japan

[73] Assignee: **SMC Kabushiki Kaisha**, Tokyo, Japan

[**] Term: **14 Years**

[21] Appl. No.: **35,986**

[22] Filed: **Mar. 10, 1995**

[30] **Foreign Application Priority Data**

Sep. 13, 1994 [JP] Japan 6-27788

[52] U.S. Cl. **D10/83; D10/85; D10/96**

[58] Field of Search ..... **D10/83, 85, 96; 73/431, 728, 861.74; 200/83 B, 83 N**

[57] **CLAIM**

The ornamental design for a solid state pressure detector, as shown and described.

DESCRIPTION

FIG. 1 is a top plan view of a solid state pressure detector, showing our new design;

FIG. 2 is a front view thereof, the rear view being a mirror image of the view shown;

FIG. 3 is a bottom view thereof;

FIG. 4 is a left side view thereof;

FIG. 5 is a right side view thereof;

FIG. 6 is a perspective view thereof; and,

FIG. 7 is a perspective view thereof on a reduced scale showing the entire solid-state pressure detector.
